MANUALLY OPERATED DRY SHAVING DEVICE

Frederick Wilfred Knowles, London, England, assignor to The Wilkinson Sword Company Limited, London, England, a British company

Application August 13, 1947, Serial No. 768,353
In Great Britain September 25, 1946

8 Claims. (Cl. 30—43)

1

This invention relates to manually operated dry shaving devices comprising a cutter device carried on an operating handle which is operatively connected through a ball joint with a support for a reticulated guard plate.

The object of the present invention is to provide a manually operated dry shaver of the kind referred to in which the parts are of simple and cheap construction and which will be reliable and efficient in operation.

In the accompanying drawings which illustrate one form of manually operated dry shaving device made according to the invention.

Fig. 1 is a vertical section through the device; Fig. 2 is a sectional plan view taken on line 2—2, Fig. 1;

Fig. 3 is a sectional plan view taken on line 3—3, Fig. 1, and

Fig. 4 is a vertical section through the cutter.

The device shown in the drawings comprises a handle 10, a guard carrier 11, and a cutter blade 12 mounted on a spindle 13 which also serves operatively to connect the handle and guard carrier.

The handle 10 is moulded from a synthetic resin and comprises a rounded end, which is solid except for an axial bore 10¹, and a flared skirt portion 10² terminating at top in a spherical recess 10³.

The guard carrier 11 is made of brass and, in addition to an outer conical portion 11¹, terminating in a cylindrical portion 11¹, it comprises an inner elongated tapering portion 11² terminating in a spherical end 11³ apertured at 15 and housed in the recess 10³. The inclination of the wall of the tapering portion 11² is less than the inclination of the wall of the flared skirt portion 10² of the handle. The wall of the conical part 11¹ is formed with a number of apertures 16 (four in the example illustrated) for the purpose hereafter described.

The guard plate 17 comprises a circular planar disc of thin steel having a large number of apertures 18 uniformly distributed over its surface and soldered in a circular bezel 19 made of mild spring steel and adapted to be sprung into position on the cylindrical portion 11¹ of the guard carrier 11. Instead of being planar the guard plate 17 may be inwardly curved, or dished, i. e. convex on the side facing the spherical end 11³.

The spindle 13 is made of steel and is provided with two intermediate parts 13¹, 13² of different diameters. An axially drilled steel ball 14 is mounted on the part 13¹ and is supported on a shoulder 20 formed between the parts 13¹, 13².

2

The ball is located nearer to the handle than to the cutter thus providing a long radius of oscillation or gyration to the cutter.

As shown in detail in Fig. 4 the cutter 12 comprises a cylindrical hub 21 having an inwardly curved or hyperboloidal axial drill 22 therein and a conical skirt 23. The apex angle of the inner wall of the skirt is 144° and the apex angle of the outer wall of the skirt is 108°, the angle α formed between the inner and outer walls being thus 18°.

The outer edge 24 of the cutter is suitably sharpened and is pressed into contact with the inner surface of the guard plate 17 by means of a spring 25 bearing between a shoulder 26 on the spindle 13 and the cylindrical hub 21 of the cutter 12.

The parts are assembled by placing the ball 14 on the part 13¹ of the spindle, aligning the handle 10, 10² and guard carrier 11, 11² (the latter without the guard plate) inserting the spindle 13 through the aligned aperture 15 and bore 10¹ and securing the end of the spindle (provided with screw thread 27) by a nut 28 located in a corresponding recess 29 in the top of the handle. The device is now inverted, first the spring 25 and then the cutter 12 placed on the spindle, and finally the bezel 19 containing the reticulated guard plate 17 is snapped on to the cylindrical end 11¹ of the guard carrier. The device is then ready for use.

It will be noted that in the arrangement described the ball 14 provides a universal movement between the handle 10 and the guard carrier 11, within limits determined by the size of the aperture 15 in the guard carrier and by the difference in inclination between the walls of the elongated part 11² of the guard carrier and of the skirt portion 10² of the handle. Moreover, the inward curvature of the drill 22 in the cutter allows of tilting of the cutter 12 in addition to movement of the cutter towards and away from the ball 14. Thus, the cutting edge can be maintained in continuous contact with the inner surface of the guard plate during any movement of the ball joint. The cutter 12 is preferably of a resilient nature to allow the cutting edge to adapt itself to any inaccuracies and changes of form of the shield.

In use, the guard plate 17 is pressed on to the surface to be shaved and a circular, spiral, or reciprocating movement is applied to the handle, whereupon the ball joint permits the guard plate 17 to roll, circumgyrate, circumvolve and rock over the surface to be shaved. During such

motion hairs on the surface to be shaved project through the perforations 18 in the guard plate and are sheared by the cutter blade. Hairs thus cut off can be evacuated through the apertures 16 in the guard carrier by appropriately shaking the device.

What I claim and desire to secure by Letters Patent is:

1. A manually operated dry shaving device comprising, in combination, an operating handle, a spindle fixed axially to, and extending beyond said handle, a support for a reticulated guard plate, said handle having a spherical socket formed therein, said support having one end thereof formed into a hollow substantially spherical shape adapted to be received in said spherical socket, means comprising a ball located on said spindle and adapted to be received in said hollow substantially spherical end of said support, whereby universal movement is provided between said handle and said support, a reticulated guard plate mounted on said support at the end thereof remote from the ball joint, said guard plate being substantially planar and a cutter device mounted on said spindle at the end thereof remote from the handle so as to cooperate with the inner surface of said guard plate, said ball being located nearer to the handle than to the cutter.

2. A manually operated dry shaving device comprising, in combination, an operating handle, a spindle extending axially through and beyond said handle, a seat on said spindle, a support for a reticulated guard plate, said handle having a spherical socket formed therein, said support having one end thereof formed into a hollow substantially spherical shape adapted to be received in said spherical socket, said support having an aperture through which said spindle passes, means comprising a ball located on said seat on said spindle and adapted to be received in said hollow substantially spherical end of said support whereby universal movement is provided between said handle and said support, a reticulated guard plate mounted on said support at the end thereof remote from the ball joint, said guard plate being substantially planar, and a cutter device mounted on said spindle at the end thereof remote from the handle so as to cooperate with the inner surface of said guard plate, said ball being located nearer to the handle than to the cutter.

3. A manually operated dry shaving device comprising, in combination, an operating handle, comprising a solid end and a hollow skirt portion terminating in a spherical recess, a spindle extending axially through and beyond said handle, a seat on said spindle, a support for a reticulated guard plate, an extension to said support projecting into the skirt portion of said handle and having an apertured spherical end through which said spindle passes, means comprising a ball located on said seat on said spindle for operatively connecting said handle to said support, the spherical end of said extension to said support being retained between the ball and said spherical recess in the handle, whereby universal movement is provided between said handle and said support, a reticulated guard plate mounted on said support at the end thereof remote from the ball joint, said guard plate being substantially planar, and a cutter device mounted on said spindle at the end thereof remote from the handle so as to cooperate with the inner surface of said guard plate, said ball being located nearer to the solid end of the handle than to the cutter.

4. A manually operated dry shaving device comprising, in combination, an operating handle, a spindle extending axially through and beyond said handle, the central part of the spindle being formed with an enlarged diameter the ends of which constitute two seats, a support for a reticulated guard plate, said support having an aperture through which said spindle passes, means comprising spherical surfaces on said support and said handle and a ball located on one of said seats on said spindle, said ball being adapted to engage the inner spherical surface of said support, whereby universal movement is provided between said handle and said support, a reticulated guard plate mounted on said support at the end thereof remote from the ball joint, said guard plate being substantially planar, a cutter device mounted on said spindle at the end thereof remote from the handle so as to cooperate with the inner surface of said guard plate, said ball being located nearer to the handle than to the cutter, and spring means for pressing said cutter device on to said guard plate, one end of said spring means bearing against the other of said seats on said spindle.

5. A manually operated dry shaving device according to claim 3 wherein the wall of said skirt portion of said handle and the wall of said extension to said support are outwardly inclined, the angle of inclination of said extension being smaller than the angle of inclination of the skirt.

6. A manually operated dry shaving device comprising, in combination, an operating handle, a spindle fixed axially to, and extending beyond said handle, a support for a reticulated guard plate, means comprising a ball located on said spindle and engaging a socket shaped surface of said support for operatively connecting said handle to said support, whereby universal movement is provided between said handle and said support, a reticulated guard plate mounted on said support at the end thereof remote from the ball joint, said guard plate being substantially planar, and a cutter device comprising a cylindrical hub mounted on said spindle at the end thereof remote from the handle so as to cooperate with the inner surface of said guard plate, said ball being located nearer to the handle than to the cutter.

7. A manually operated dry shaving device according to claim 6 wherein said cutter device comprises a conical skirt depending from said cylindrical hub, the outer edge of said conical skirt being sharpened to constitute a cutting edge.

8. A manually operated dry shaving device according to claim 6 wherein said cylindrical hub is axially drilled with an inward (hyperboloidal) curvature to permit of tilting on the spindle.
